US0D1113738S

(12) **United States Design Patent** (10) **Patent No.:** **US D1,113,738 S**
(45) **Date of Patent:** **** Feb. 17, 2026**

(54) **TRAY FOR CARD CONNECTOR**

(71) Applicant: **Japan Aviation Electronics Industry, Limited**, Tokyo (JP)

(72) Inventor: **Kei Takano**, Tokyo (JP)

(73) Assignee: **Japan Aviation Electronics Industry, Limited**, Tokyo (JP)

(**) Term: **15 Years**

(21) Appl. No.: **29/766,433**

(22) Filed: **Jan. 15, 2021**

(30) **Foreign Application Priority Data**

Jul. 28, 2020 (JP) ..... 2020-015615 D

(51) **LOC (15) Cl.** **13-03**

CLAIM

The ornamental design for a tray for card connector as shown and described.

DESCRIPTION

FIG. 1 is a front elevational view of a tray for card connector showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right and bottom side thereof; and,

FIG. 10 is a perspective view showing a rear, left and top side thereof.

1 Claim, 5 Drawing Sheets
